BATTER SPOON

William R. Byrd, Erie, Pa.

Application July 27, 1953, Serial No. 26,157

Term of patent 14 years

(Cl. D44—29)

FIG. 1

FIG. 2

To all whom it may concern:

Be it known that I, William R. Byrd, a citizen of the United States, residing at Erie, in the county of Erie and State of Pennsylvania, have invented a new, original, and ornamental Design for a Batter Spoon, of which the following is a specification, reference being had to the accompanying drawing, forming part thereof.

In the drawing:

Fig. 1 is a top perspective view of a batter spoon, showing my new design;

Fig. 2 is a side perspective view thereof; and

Fig. 3 is a bottom perspective view thereof.

I claim:

The ornamental design for a batter spoon, as shown.
